[57] CLAIM

The ornamental design for a garage door opener housing, as shown and described.

DESCRIPTION

FIG. 1 is a perspective view of a garage door opener housing showing our new design;

FIG. 2 is a right-hand side elevational view thereof;

FIG. 3 is a bottom plan view thereof;

FIG. 4 is an inverted left-hand side elevational view thereof;

FIG. 5 is a top plan view thereof;

FIG. 6 is a rear elevational view thereof; and,

FIG. 7 is a front elevational view thereof.

The broken line showing is for illustrative purposes only and forms no part of the claimed design.
